UNITED STATES PATENT OFFICE

2,056,357

VACUUM BREAKER

Henry J. Luff, Cleveland Heights, Ohio, assignor
to Mary A. M. Luff, Cleveland Heights, Ohio

Application May 9, 1936, Serial No. 78,771

6 Claims. (Cl. 137—111)

This invention relates to vacuum breakers such as are adapted to function in the flush water supply line of a closet or like plumbing fixture, between the fixture and its flush valve in the line, to prevent back siphonage of waste water from the fixture into the line, as should a vacuum occur in the line coincident with an overflow condition in the fixture.

My Patent 2,023,178 of December 3, 1935, shows such a vacuum breaker characterized by nozzle means disposed within vented pipe means to provide a main stream for flushing water, and a vented auxiliary stream having distribution thereabout and arranged in parallel relation with the main stream, that is separating from the main stream above the vent in the pipe means and returning to commingle with the main stream below the vent.

My Patent No. 2,045,479 issued June 23, 1936, shows improvements in vacuum breakers of the type disclosed in my said patent, such improvements including means providing for adjustment of the size of the auxiliary stream, and consequently of the relation between main and auxiliary streams. Factors determining the proper relation between the main and auxiliary passages, are principally normal pressure in the supply line and the amount of vacuum which might occur in the line, as determined for example by the elevation of the breaker above the inlet of the line. Means for such control is characterized by provision for selective employment in the breaker assembly, of nozzle means of the proper capacity, and for adjustment of the nozzle means in the assembly relative to a member cooperative with the nozzle means to restrict the auxiliary passage. The structure employed for the purpose provides a straight through main passage and a relatively small and devious generally annular auxiliary passage.

As also shown in my said application, a Venturi restriction is preferably provided in the pipe means for the purpose of assisting the main stream to induce flushing flow of the auxiliary stream, and it is desirable that such Venturi restriction be of capacity corresponding with that of the nozzle means.

The present invention constitutes generally further improvements in vacuum breakers of the character described, and more particularly, provision of means preventing obstruction of the auxiliary passage by accumulations of sand or like matter entrained in the supply stream, provision for more convenient mounting of the selected nozzle means in the breaker assembly, provi-

sion of a sub-assembly of the nozzle means and its immediately cooperative auxiliary passage controlling member as a unit, provision for selective employment of Venturi restriction corresponding to the selected nozzle means, and withal a simpler 5 construction.

The exact nature of this invention together with further objects and advantages thereof will be apparent from the following description taken in connection with the accompanying drawing, in 10 which Fig. 1 is a typical sectional elevation as in the longitudinal plane of line 1—1, Fig. 2, of a breaker constructed in accordance with this invention, parts between which the breaker is connected being indicated in broken lines, flushing 15 water flow being indicated by arrows, and air flow as in emergency conditions being indicated by broken arrows; and Fig. 2 is a transverse section as in the plane of line 2—2, Fig. 1.

With reference now to the drawing, the 20 breaker comprises pipe means generally indicated at 1, vertically disposed, having connection at its upper end with a flush water supply line to be subject to a flush valve, as conventionally indicated at A, and at its lower end having connection to a closet or like plumbing fixture by means conventionally indicated at B. More particularly the pipe means is constructed as here shown, of two principal parts, a tubular part 1a, to the upper end of which is brazed or otherwise 25 permanently secured a head part 1b, the latter being internally threaded as indicated, for its supply connection with the member A. The head is suitably deformed, as hexagonally, at 1d as indicated in the drawing, to accommodate a 30 wrench for making the connection with the member A.

The pipe means is provided with a slight internal projection 1c which may be annular as indicated, and which forms a shouldered recess 40 within which an annular sleeve generally indicated at 2 may seat. The sleeve 2 has an offset portion 2a forming a shoulder against which a gasket A' seats, the gasket being located at the end of the member A so that the sleeve 2 is firmly 45 secured in its illustrated position at the inlet end of the vacuum breaker by the connection of the latter with the supply member A.

The lower part of the sleeve 2, is internally 50 threaded to receive a flange part 3a of the nozzle means generally indicated at 3. The nozzle flares outwardly as at 3b as it extends above the flange part 3a, and extends cylindrically below the flange part 3a as at 3c, the part 3c being permanently secured to the part 3b as by brazing at 55

the shown threaded connection between these parts. The flange part 3a of the nozzle is perforate as by a number of openings 3d circumferentially disposed about and closely adjacent the part 3c.

The upper portion of the sleeve 2 fits within the supply member A and is provided with an annular internal lip 2b overhanging the periphery of the inlet end part 3b of the nozzle, and preferably chamfered as indicated to minimize its obstruction to flow.

The pipe means 1 is provided with vent openings 1e adjacent the nozzle 3 and the nozzle is provided with deformations accessible through the vent openings 1e by which a rotational adjustment of the nozzle in the sleeve 2 may be had. Such deformations are here shown as circumferentially spaced pins 3e brazed or otherwise permanently secured in the flange part 3a of the nozzle, and projecting downwardly therefrom into the zone of the vent openings of the pipe means.

The head part 1b of the pipe means is externally threaded to receive an annular skirt 1f arranged to overhang and thus conceal and protect the vent openings 1e. A Venturi restriction 1g is provided within the pipe means below the nozzle means as indicated, the pipe means preferably converging as shown to provide a locating seat for the restriction 1g. The restriction 1g may have brazed connection with the pipe part 1a or it may be positioned merely by its seat therein so as to be conveniently removable for replacement by a different size if desired.

As to operation, it will be apparent that during the flushing period the breaker being supplied with water under pressure through the member A, most of this water will pass straight downwardly through the nozzle 3, the Venturi restriction 1g, and thence from the breaker to the fixture served thereby. Part of the flushing water, however, will pass radially outwardly through the annulus between the lip 2b of the sleeve 2 and the peripheral extremity of the upper part 3b of the nozzle, thence downwardly between nozzle and sleeve, thence through the openings 3d in the nozzle flange part 3a, thence downwardly about the cylindrical nozzle portion 3c immediately therebelow rejoining the water of the main stream, and passing with the latter through the Venturi restriction 1g. It will be apparent that the lip 2b will prevent particles entrained in the incoming stream from entering the auxiliary passage, these particles instead being caused to pass through the smoothly walled main passage provided by the nozzle. The form and capacity of the Venturi restriction is such that the combined streams will effectively occupy its throat so that substantially no air will be drawn into the vent openings 1e of the breaker during the normal flushing operation.

Should a high vacuum occur in the supply line, during a flushing operation, air will be admitted through the vent openings 1e in the pipe means and thence flow upwardly through the described auxiliary passage breaking the vacuum in the supply line. Meanwhile the inertia of the main stream within and below the nozzle will empty the liquid in the breaker, into the fixture.

It will be apparent that a fine adjustment of the auxiliary stream may be had by rotating the nozzle upon its mounting threads in the sleeve 2 by means of the pins 3e and thus adjusting the longitudinal dimension of the restricting annu-

lus immediately beneath the lip 2b of the sleeve. For such adjustment the skirt 1f is unscrewed from its threads upon the pipe head part 1b and lowered to permit access to the Venturi openings 1e and therethrough to the pins 3e. It will be noted that the action of the auxiliary stream is clearly observable during the adjustment. And hence the proper adjustment for the given operating conditions is easily accomplished.

Should it be desired to change the capacity or general characteristics of the breaker to suit other conditions, upon disconnecting the breaker from its inlet member A, the assembly of nozzle and sleeve may be removed as a unit simply by lifting from the pipe means.

What I claim is:

1. A vacuum breaker adapted to be disposed in the flush water supply line of a closet or like plumbing fixture, and comprising pipe means adapted for disposition between the fixture and its flush valve in said line, and nozzle means disposed within said pipe means to provide a main passage for flushing water and an auxiliary passage in parallel relation to said main passage and distributed thereabout, said pipe means having vent means for said auxiliary passage, said pipe means and said nozzle means having annular portions disposed in longitudinally spaced relation, with that of said pipe means overhanging that of said nozzle means, said portions confining said auxiliary passage therebetween, and means providing for adjustment of one of said confining portions relative to the other to control flow through said auxiliary passage.

2. A vacuum breaker adapted to be disposed in the flush water supply line of a closet or like plumbing fixture, and comprising pipe means adapted for disposition between the fixture and its flush valve in said line, and nozzle means disposed within said pipe means to provide a main passage for flushing water and an auxiliary passage in parallel relation to said main passage and distributed thereabout, said pipe means having vent means for said auxiliary passage, said pipe means and said nozzle means having annular portions disposed in longitudinally spaced relation, with that of said pipe means overhanging that of said nozzle means, said portions confining said auxiliary passage therebetween, and threaded parts arranged to be effective to provide relative longitudinal adjustment between said confining portions, to control flow through said auxiliary passage.

3. A vacuum breaker adapted to be disposed in the flush water supply line of a closet or like plumbing fixture, and comprising pipe means adapted for disposition between the fixture and its flush valve in said line, and nozzle means disposed within said pipe means to provide a main passage for flushing water and an auxiliary passage in parallel relation to said main passage and distributed thereabout, said pipe means having vent means for said auxiliary passage, said pipe means and said nozzle means having annular portions disposed in longitudinally spaced relation, with that of said pipe means overhanging that of said nozzle means, said portions confining said auxiliary passage therebetween, and threaded parts arranged to be effective to provide longitudinal adjustment of said nozzle means, to control flow through said auxiliary passage.

4. A vacuum breaker adapted to be disposed in the flush water supply line of a closet or like plumbing fixture, and comprising pipe means adapted for disposition between the fixture and

- its flush valve in said line, a sleeve at the inlet end of said pipe means, nozzle means threadedly mounted in said sleeve to provide a main passage for flushing water and an auxiliary passage in parallel relation to said main passage and distributed thereabout, said sleeve and said nozzle means having annular portions disposed in longitudinally spaced relation to confine said auxiliary passage therebetween, said sleeve being mounted at the inlet end of said pipe means to be secured by the inlet connection of said pipe means and to be removable with said nozzle means as a unit, said pipe means having vent means for said auxiliary passage.
5. A vacuum breaker adapted to be disposed in the flush water supply line of a closet or like plumbing fixture, and comprising pipe means adapted for disposition between the fixture and its flush valve in said line, a sleeve at the inlet end of said pipe means, nozzle means threadedly mounted in said sleeve to provide a main passage for flushing water and an auxiliary passage in parallel relation to said main passage and distributed thereabout, said sleeve and said nozzle means having annular portions disposed in longi-
- 10 tudinally spaced relation with that of said pipe means overhanging that of said nozzle means, to confine said auxiliary passage therebetween, said sleeve being mounted at the inlet end of said pipe means to be secured by the inlet connection of said pipe means and to be removable with said nozzle means as a unit, said pipe means having vent means for said auxiliary passage.
- 15 6. A vacuum breaker adapted to be disposed in the flush water supply line of a closet or like plumbing fixture, and comprising pipe means adapted for disposition between the fixture and its flush valve in said line, and nozzle means disposed within said pipe means to provide a main passage for flushing water and an auxiliary passage in parallel relation to said main passage and distributed thereabout, said pipe means having vent means for said auxiliary passage, a Venturi restriction disposed within said pipe means to be cooperative with said nozzle to assist flow in the auxiliary stream provided by said auxiliary passage, said pipe means having a downwardly convergent portion and said Venturi restriction seating within said portion.
